(57) **CLAIM**

The ornamental design for a self-balancing vehicle, as shown and described.

DESCRIPTION

FIG. 1 is a front view of a self-balancing vehicle showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front side perspective view thereof; and,

FIG. 8 is a rear side perspective view thereof.

The broken lines in the drawing depict portions of the self-balancing vehicle that form no part of the claimed design.
